UNITED STATES PATENT OFFICE.

ALFRED L. RUTHVEN, OF ROCHESTER, NEW YORK.

SIMPLEX TRAIN CONTROL.

Application filed July 31, 1922, Serial No. 573,742. Renewed September 3, 1925.

To all whom it may concern:

Be it known that I, ALFRED L. RUTHVEN, a citizen of the United States, residing at Rochester, in the county of Monroe and State of New York, have invented certain new and useful Improvements in Simplex Train Control, of which the following is a specification, reference being had therein to the accompanying drawing.

10 The present invention relates to train controlling apparatus, and is particularly an improvement over the apparatus disclosed in my copending application Serial No. 549,705, filed April 5, 1922.

15 It is the object of the invention to provide a train or vehicle controlling apparatus of the same general kind as disclosed in said application with improvements, arrangements of the component elements and alterations rendering the apparatus more simple in construction, as well as increasing the utility and efficiency thereof, the general objects of the present invention being substantially the same as those mentioned in 20 said application supra.

25 With the foregoing and other objects in view, which will be apparent as the description proceeds, the invention resides in the construction and arrangements of parts, as hereinafter described and claimed, it being understood that changes can be made within the scope of what is claimed, without departing from the spirit of the invention.

30 The invention is illustrated in the accompanying drawing, wherein the figure is a diagrammatical view of the apparatus.

35 The responsive devices or impulse receivers of the vehicle equipment comprises the choke coils 7 and 8 which are wound on the respective cores 9 and 10. A non-magnetic section 11 is disposed in one rail 12 of the track at each controlling station, rendering the rail non-magnetic at each and every controlling station, with the portions of the rail in the blocks or between the controlling stations of magnetic material. The choke coils or receivers of the vehicle equipment move closely over the rail whereby when the vehicle is traveling between 40 controlling stations, the magnetic portion of the rail 12 substantially completes the magnetic circuits of the cores 9 and 10, the ends of said cores being extended toward and closely adjacent to the rail, whereas when 45 the coils move over the non-magnetic rail section 11 the magnetic circuits are interrupted, the same as if a complete air gap existed between the terminals of the cores 9 and 10. Two of the choke coils or receivers are employed at longitudinally spaced points in order that when passing non-magnetic crossings, frogs, switch points, and the like, only one of the coils, at the same time, will pass over such non-magnetic portions of the rail, and the coils are so arranged that they 50 will only simultaneously move over the non-magnetic rail section 11 and no other non-magnetic portions of the rail. This will avoid false impulses or responses in the vehicle equipment should non-magnetic portions be used in the rail between the controlling stations. Furthermore, such non-magnetic portions of the rail in the blocks or between controlling stations can be rendered magnetic by placing iron bars or 55 bodies adjacent to the non-magnetic portions or by rendering the non-magnetic portions magnetic in any other way, as will be readily apparent to those skilled in the art.

60 A predetermined condition of the vehicle equipment is obtained each and every time the vehicle passes a controlling station, by the presence of the non-magnetic section in the rail, for producing danger or vehicle stopping control of the vehicle, and controlling means are associated with the non-magnetic rail section for offsetting or modifying the control established by the non-magnetic rail section to obtain caution, clear or 65 other modified conditions. For this purpose, magnetic cores or armatures 13 are assembled with the non-magnetic rail section 11, being preferably applied to and supported from said rail section with their terminals or poles directed upwardly closely adjacent to the tread of the rail, and said cores 13 are spaced apart longitudinally of the non-magnetic rail section at suitable points. Coils 14 are wound on the intermediate portions of the cores 13, and are disposed in circuits with the inductive resistance coils 16 and switches 17, and said switches are under the control of electro-magnets 18 disposed in the circuits of the 70 wayside or semaphore signal apparatus, whereby when the electro-magnets 18 are energized, the switches 17 are held closed, said switches dropping open when the magnets are deenergized. The control over the 75

magnets 18 and switches 17 forms no part of the present invention. It may be here noted that the track elements being assembled with and disposed below the rail do not constitute an objectionable obstruction on the track, and are protected by the rail from being knocked-off, damaged, or the like. The choke coils or receivers of the vehicle being disposed over the rail do not constitute an objectionable obstruction on the vehicle which would be apt to be knocked-off, damaged or damage-productive, thereby avoiding the problem of clearances, and providing for a given uniform clearance between the vehicle and track devices by associating them with the rail.

A solenoid or electro-magnetic translating device 19 is controlled by the choke coils 7 and 8, and such translating device includes the vertically movable core or slide 20 which drops by gravity when the solenoid is de-energized. The solenoid is normally energized when travelling in the block, by means of an alternating or fluctuating current generator 21, the coils 7 and 8 being connected in series with the solenoid. The circuit includes the generator 21, a conductor 22, coil 7, conductors 24 and 25, coil 8, conductor 26 including the condenser or capacity react-
ance 27, solenoid 19, conductor 28, contact 29, a slide switch 30 carried by a rod or stem 31 attached to the core 20, and a conductor 32 connecting said slide switch 30 and the generator 21. The condenser 27 is of such capacity and adjustment with reference to the coils 7 and 8, that when said coils are over the iron or magnetic portion of the rail, whereby the magnetic flux in the cores 9 and 10 can flow freely therethrough, the circuit of the solenoid 19 is tuned and said solenoid is energized to the maximum strength of the current, thereby supporting the core 20 in its elevated position as shown, whereas when the choke coils 7 and 8 both pass over a non-magnetic portion or section 11, the magnetic circuits of the cores 9 and 10 being interrupted or broken, will result in a magnetic reluctance in the cores 9 and 10 and a choking effect established by the coils 7 and 8, thereby detuning the circuit of the solenoid 19, to sufficiently deenergize said solenoid to release the core 20 for downward movement. Such detuning action is obtained by the proper winding and location of the coils 7 and 8 and the proper capacity and adjustment of the condenser 27. When such deenergization of the solenoid is obtained in reaching a non-magnetic rail section at a controlling station, the dropping of the core 20 will immediately remove the slide switch 30 from the contact 29, thereby opening the circuit of the solenoid and preventing said solenoid from being reenergized until the core or slide 20 has been restored—that is, the deenergization of the

solenoid in permitting the core 20 to drop will not enable the core to be picked up by the solenoid without other actions occurring. The circuit of the coils 7 and 8 and solenoid 19 is so tuned, that when one coil is over a non-magnetic portion while the other coil is over a magnetic portion of the rail, the circuit is not sufficiently detuned to deenergize the solenoid to such an extent as to release the core 20.

When passing a controlling station, the responsive devices after having deenergized the solenoid 19, now control a solenoid or electro-magnetic device 33, constituting a secondary translating device operable for obtaining caution and clear or other modified conditions after a danger condition is established by the deenergization of the solenoid or primary translating device 19. The solenoid 33 controls a step by step ratchet device 34 for obtaining caution and clear conditions in progressive succession, and includes a wheel 35 having the ratchet teeth 36, such wheel being weighted or otherwise biased to turn, when released, to the normal position illustrated. A pawl 37 is pivoted to the core 38 of the solenoid 33, and said core is projected by a spring 38' when the solenoid is deenergized to position the pawl for engaging one of the ratchet teeth 36. The pawl normally swings by gravity or otherwise away from the wheel 35, and an electro-magnet 39 is provided for picking up the pawl and swinging same into engagement with the corresponding tooth 36. The solenoid 33 and magnet 39 are brought into circuit with the generator 21 and choke coil 7 when the solenoid 19 has been deenergized and the core 20 started on its downward movement, a contact 40 being so arranged as to be engaged by the slide switch 30 the moment the core 20 starts downwardly. The circuit referred to includes the generator 21, conductor 22, choke coil 7, conductor 44 including the condenser or capacity re-
actance 45, solenoid 33, conductor 43, mag-
net 39, conductor 41, contact 40, slide switch 30 and conductor 32. It will be noted that whereas both coils 7 and 8 are connected in series with the solenoid 19, to avoid said solenoid being deenergized when passing over non-magnetic crossings, frogs, switch points, and the like, only the choke coil 7 is connected in series with the solenoid 33, the choke coil 8 being idle in so far as solenoid 33 is concerned when passing the non-magnetic rail section, so that only the coil 7 is responsively cooperable with the track elements. The condenser 45 is of such capacity and adjustment that when the core 9 is over the non-magnetic rail section 11, the solenoid 33 and magnet 39 are energized sufficiently (the circuit thereof being tuned) to raise the pawl 37 and attract the core 38 for advancing the wheel 35 one step, such

preliminary step of the wheel always occurring, in any event, when passing a controlling station and changing the control from the solenoid 19 to the solenoid 33. If the core 9 is over a core 13 with the corresponding switch 17 closed, the result is the same, just as if the track element were absent, and the core 13 completing the magnetic circuit of the core 9 will even slightly increase the current flowing through the solenoid 13 and magnet 39 to avoid the pawl 37 being released. However, when the core 9 passes over a core 13 with the corresponding switch 17 open, a signal impulse will be transmitted from the track to the vehicle equipment. Thus, the magnetic flux flowing from the core 9 through the core 13 will set up an alternating current in the secondary coil 14 and circuit thereof, and the coils 14 and 16 will impede the flow of current in the track circuit, thereby resisting and impeding the flow of magnetic flux both in the core 13 and the core 9, resulting in a choking effect being obtained in the coil 7 and detuning of the circuit of the solenoid 33 and magnet 39. Accordingly, the solenoid 33 and magnet 39 are deenergized sufficiently, for a moment, to release the pawl 37 and core 38, the pawl dropping away from the wheel 35 and the core 38 being projected by the spring 38'. As soon as the core 7 has left the core 13, the choking and detuning influence is lost and the solenoid 33 and magnet 39 are again energized to raise the pawl 37 and attract the core 38, thereby advancing the wheel 35 a second step. The same action will occur if the coil 7 passes the second core 13 with the corresponding switch 17 open, thereby providing for one or more impulses in the vehicle equipment for turning the wheel 35 the corresponding number of steps, which is for the purpose of setting up caution or clear conditions after the danger condition has been established in reaching the non-magnetic rail section.

An electro-magnet 46 or other translating device controls the movement of the vehicle, and, as shown, is normally energized to attract and close a switch 46', it being understood that the magnet 46 being deenergized will release the switch 46' and in any suitable manner provide a vehicle stopping signal or condition such as by applying the air brakes, or the like. The circuit of the magnet 46 is broken, under different conditions, for retarding or stopping the movement of the vehicle, and the normal closed circuit of the magnet 46 includes the battery 47 or other source of current, conductor 48, magnet 46, contact 49, switch 46' normally engaging said contact, conductor 50, contacts 51, switch segment 52 of the wheel 35 normally engaging said contacts, conductor 53, contact 54, slide switch 55 carried by the rod

31 normally engaging said contacts 54 and conductor 56. The circuit of the magnet 46 can thus be broken by the movement of the wheel 35 two steps to remove the switch segment 52 from the contacts 51 or by the downward movement of the core 20 and slide switch 55 a sufficient amount to remove said switch 55 from the contact 54.

The breaking of the circuit of the magnet 46 by the switch 55 is retarded, thereby requiring a predetermined distance of travel of the vehicle, when passing a controlling station, before the switch 55 leaves the contact 54 to break the circuit of the magnet 46 and apply the brakes. Thus, a finger 57 is pivoted to the rod or stem 31 to swing downwardly but not upwardly from its normal position, and said finger is arranged to drop into engagement with the worm 58 when the core 20 is released. Said worm 58 is mounted on a shaft 59 that is driven from a wheel, axle or other movable part of the vehicle, so that the worm is rotated according to the movement of the vehicle. The operative connection preferably includes suitable gearing 60 for rotating the worm 58 in the same direction when the vehicle moves in either direction. Thus, when the core 20 is released, the finger 57 dropping into engagement with the worm 58 will retard the downward movement of said core and the slide switches 30 and 55, in order to delay the movement of the core and slide switches to the lowermost position until the vehicle has moved a predetermined distance and the coil 7 has had an opportunity of passing the track elements. This will delay the complete establishment of danger or vehicle stopping conditions until there has been an opportunity for establishing caution or clear conditions.

In order to restore the core 20 to normal position, after the non-magnetic rail section has been passed and the required predetermined distance travelled, means is provided for the reenergization of the solenoid 19. Thus, a contact 61 is connected to the conductor 28 and is arranged to be engaged by the slide switch 30 when the core 20 reaches its lowermost position, thereby closing the circuit of the solenoid 19, said switch 30 only engaging the contact 61 when the coils 7 and 8 have moved beyond the rail section 11. Such circuit includes the generator 21, conductor 22, coil 7, conductors 24 and 25, coil 8, conductor 26, solenoid 19, conductor 28, contact 61, slide switch 30 and conductor 32. In order to maintain such circuit through the solenoid 19 closed while the core 20 and slide switch 30 are being elevated, the slide switch 30 leaving the contact 61 in its upward movement, a switch 62 is provided to be attracted to the solenoid 19 when said solenoid is energized by the engagement of the switch 30 with the contact 61 which take

place after the coils 7 and 8 have moved past the rail section 11. Such switch 62 is connected by a branch conductor 63 with the conductor 32, and a weight 64 holds the switch 62 open unless attracted by the energization of the solenoid 19. A contact 65 is connected to the conductor 28 to be engaged by the switch 62 when it is closed. Thus, when the switch 30 engages the contact 61 to energize the solenoid 19, the switch 62 is attracted to the solenoid and brought against the contact 65. This closes a circuit including the generator 21, conductor 22, coil 7, conductors 24 and 25, coil 8, conductor 26, solenoid 19, conductor 28, contact 65, switch 62, conductor 63 and conductor 32. The switch 62 therefore shunts the switch 30 and keeps the circuit of the solenoid 19 closed during the upward movement of the core 20 and slide switches. A pin 66 is carried by the rod 31 in order that when the core 20 is completely raised to bring the slide switch 30 into engagement again with the contact 29, the pin 66 will engage the switch 62 and swing same open, as illustrated, thereby again providing normal conditions, the circuit of the solenoid 19 being completed, as in the first instance described, by way of the contact 29 and switch 30, whereby upon deenergization of the solenoid when a non-magnetic rail section is reached, the circuit of the solenoid 19 is broken the moment the switch 30 leaves the contact 29.

The wheel 35 is held in its first and second steps, against return movement, by means of a holding or detent electro-magnet 67. The wheel 35 has armature horns or projections 68 and 68' to move adjacent to the pole of said magnet 67 when the wheel is advanced one and two steps, respectively, and either horn or projection being brought adjacent to the pole of the magnet will be attracted thereto in order to prevent the wheel returning unless the magnet is deenergized. The circuit of the magnet 67 is normally open, and the pawl 37 being normally removed from the wheel 35, will permit said wheel to turn back to initial or normal position. When the core 20 is released from the solenoid 19 in reaching a controlling station, the magnet 67 is energized so as to be capable of holding the wheel 35. For this purpose, a contact 75 is so arranged as to be engaged by the slide switch 55 the moment the core 20 drops, and the circuit of the magnet 67 would then include the battery 47, conductor 69, magnet 67, conductor 70, contacts 71, a switch segment 72 of the wheel 35 normally engaging said contacts, conductor 73, conductor 74, contact 75, slide switch 55 which has started downwardly, and conductor 56. When the magnet 67 is energized, it attracts a shunt switch 76 connected to the conductor 70 and brings said switch 76 against a contact 77 connected to the conductor 74. Thus, even though the wheel 35 moves one step, to remove the switch segment 72 from the contacts 71, the contacts 71 are shunted by the switch 76, and instead of the circuit of the magnet 67 being completed by way of the contacts 71 and segment 72, the current flows from the magnet 67 through the switch 76 and contact 77 to the conductor 74, thereby keeping the magnet energized. The switch 76 thus replaces the switch segment 72 when the wheel 35 has been turned, to keep the circuit of the magnet closed, and said switch 76 is so arranged that it can be manually moved against the contact 77, as will hereinafter appear.

Caution conditions are established when the wheel 35 is turned two steps, thereby removing the switch segment 52 from the contacts 51, said segment 52 in this case moving forward to bridge a pair of contacts 78, and another pair of contacts 91, which are normally insulated apart, are also bridged by the wheel 35 in this second step position of said wheel. A conductor 79 connects one contact 78 with the magnet 46 between said magnet and the contact 49, and a conductor 80 connects the other contact 78 with a contact 81 arranged to be engaged by the slide switch 55 the moment the core 20 starts to drop. Thus, while passing the controlling station with the core 20 down, and the wheel 35 advanced a second step, the magnet 46 is kept energized until the predetermined distance of movement of the vehicle, defined by the worm 58, has been made. The circuit of the magnet 46 will then include (the switch segment 52 having been removed from the contacts 51) the battery 47, conductor 48, magnet 46, conductor 79, contacts 78 and segment 52, conductor 80, contact 81, slide switch 55 in its downward movement, and conductor 56. The magnet 46 is thus kept energized, in the second step of the wheel 35, as long as the slide switch 55 is below its normal uppermost position, thereby preventing the immediate application of the brakes and giving an opportunity for a clear condition being established before the predetermined distance of travel of the vehicle has been accomplished. However, when such distance has been travelled resulting in the solenoid 19 being reenergized and the core 20 raised to remove the slide switch 55 from the contact 81, the circuit of the magnet 46 is broken. Thus, the segment 52 having been removed from the contacts 51 the circuit of the magnet 46 is opened at the switch 46', and the switch 55 having been raised above the contact 81 is opened the circuit of the magnet 46 at this point also. Therefore, unless the circuit of the magnet 46 is closed at some other point, the brakes will be applied for retarding the vehicle. Under these conditions,

a restrictive speed control means is operable for energizing the magnet 46 below a pre-determined speed limit, of say fifteen miles per hour, and deenergizing said magnet to prevent such speed limit being exceeded. Thus, contact strips 82 and 83 are arranged to be bridged by a switch 84 operated by a speed governor 85 that is mounted on the shaft 59, said switch bridging the contact strips when the vehicle is travelling at a speed below the permissible speed, and the switch leaving the strips when such speed is exceeded. The strip 82 is connected to the conductor 80, and a conductor 86 connects the strip 83 and the conductor 56. Therefore, with the wheel 35 in its second step position and the core 20 restored, the circuit of the magnet 46, when the vehicle is travelling below the speed limit, is closed by way of the switch 84, the switch 84 being in engagement with the strips 82 and 83 when the vehicle is travelling under caution speed. Such circuit includes the battery 47, conductor 48, magnet 46, conductor 79, contacts 78, switch segment 52 in its second position, conductor 80, strip 82, switch 84, strip 83, conductor 86 and conductor 56. Said circuit only remains closed when the vehicle is travelling at a slow speed, and should the speed limit be exceeded the switch 84 in being removed from the contact strips 82 and 83 will open the circuit resulting in the magnet 46 being deenergized and the vehicle stopping condition established, until the vehicle speed is reduced to bring the switch 84 back against the contact strips.

The circuit of the magnet 67 is broken by the movement of the wheel 35 to its third position or step, and also under caution conditions, by the vehicle reaching the end of the block, in order that the wheel 35 can return to normal or initial position. When the wheel 35 is in its second position, the slide switch 55 having been raised away from the contact 75, the circuit of the magnet 67 now includes the battery 47, conductor 69, magnet 67, switch 76, contact 77, conductor 74, branch conductor 87, one of the pair of contacts 88, switch 89 normally engaging said contacts, conductor 90 leading from the other contact 88, a pair of contacts 91, the wheel 35 bridging said contacts 91 in the second position of the wheel, a conductor 92 leading from the second contact 91, a switch 93, a contact 94 normally engaged by said switch 93, and a conductor 95 leading back to the battery 47. Thus, in the second position of the wheel 35, with the switch 55 raised, the circuit of the magnet 67 is completed through the switch 89, contacts 91, wheel 35 and switch 93. The switch 89 is opened by the movement of the wheel 35 the third step. Thus, the switch 89 is pivotally mounted adjacent to the wheel 35 and has an arm 96 disposed between a pair of pins 97 and 98 on the wheel 35. A spring 99 engages the switch 89 to throw it to either position when the switch is moved beyond intermediate or neutral position and to hold the switch in either position. When the wheel 35 is moved the third step, the pin 98 strikes the arm 96 and swings the switch 89 away from the contacts 88, the spring 99 completing the opening movement of the switch 89 and holding said switch open until again closed. The circuit of the magnet 67 is thus broken, to release the wheel 35 and it will immediately turn back to initial position. The pin 97 strikes the arm 96 when the wheel has returned to initial position, thereby swinging the switch 89 to closed position, assisted by the spring 99 which holds the switch against the contacts 88.

The caution terminating switch 93 is located adjacent to the solenoid 19 so as to be held closed when the solenoid 19 is energized in travelling through the block between controlling stations. Thus, assuming that the wheel 35 is in its second position with the switch 89 closed and the contacts 91 bridged by the wheel 35, the circuit of the magnet 67 will remain energized to attract and hold the armature horn or projection 68' of the wheel 35 to keep said wheel in its second or caution position through the block, thereby placing the control of the magnet 46 on the speed restrictive switch 84. When the train reaches the end of the block where a rail section 11 is located, the choke coils 7 and 8, as hereinbefore described, in passing over the non-magnetic rail section will result in the solenoid 19 being deenergized. Consequently, the switch 93 is released, and will open, thereby opening the circuit of the magnet 67 and permitting the wheel 35 to return to initial position the moment the core 20 is released, and before the coil 7 passes the track coils 14. The caution control is thus terminated at the end of the block as soon as the non-magnetic section is reached.

In order that the vehicle can proceed, after having been stopped, a starting means is provided for establishing caution conditions while the vehicle is at rest, permitting the vehicle to proceed under restricted speed after danger conditions have been established and the vehicle brought to a stop. Thus, a pair of contacts 101 is arranged to be bridged by the switch 84 when the governor 85 is stopped by the stopping of the vehicle, said switch being removed from said contacts when the vehicle is in motion. One contact 101 is connected by a conductor 102 with the battery conductor 48, and the other contact 101 is connected by a conductor 103 with a permissive starting switch 104 that can be manually closed against a contact 105 by an authorized person. The contact 105

is connected by a conductor 106 with a solenoid 107 and the other terminal of the solenoid is connected by a conductor 108 with the battery conductor 95. Thus, with the vehicle at rest and the switch 84 on the contacts 101, the switch 104 can be closed for closing the circuit of the solenoid 107 including the battery 47, conductor 102, contacts 101 and switch 84, conductor 103, switch 104 when closed, conductor 106, solenoid 107, and conductors 108 and 95. The energization of the solenoid 107 is used for advancing the wheel 35 to caution position, just the same as if it were advanced by the operation of the pawl 37 when the vehicle equipment receives a caution signal or impulse from the track. Thus, the core 109 of the solenoid is connected by a flexible element 110 with the wheel 35, whereby when the core is attracted into the solenoid, the flexible element 110 pulls the wheel 35 to its second or caution position, but no further, said element 110 not interfering with the rotation of the wheel in any other way. It requires the vehicle to be at rest with the switch 84 on the contacts 101 and the switch 104 to be closed by hand in order to energize the solenoid 107 to turn the wheel 35 to caution position. Thus, when the vehicle has been stopped by a danger signal, with the switch 55 moved downwardly away from the contact 54 and the magnet 46 deenergized to release the switch 46', said switch remains open to stop the vehicle, and the vehicle is compelled to come to a full stop because of the magnet 46 being deenergized and the switch 46' remaining open even though the core 20 and slide switches 30 and 55 have been restored after the movement of the vehicle the required distance past the rail section 11. Now, by closing the switch 104 the solenoid 107 is energized to turn the wheel 35 to caution position, thereby bridging the contacts 78 by the segment 52 and closing the circuit of the magnet 46 by way of the conductor 79, contacts 78, segment 52, conductor 80, contact strip 82, switch 84, contact strip 83, conductor 86 and conductor 56. This will attract the switch 46' to closed position, permitting the vehicle to proceed; but the vehicle controlling magnet 46 is under restricted speed control, as under caution conditions, inasmuch as the circuit of the magnet 46 is completed through the restrictive speed switch 84. The wheel 35 having been moved to its second position, the circuit of the magnet 67 is closed by way of the switch 89, contacts 91 and wheel 35 and switch 93 as hereinbefore described; under caution conditions, so that when the end of the block is reached, the caution control is eliminated as hereinbefore described, to clear the vehicle, providing the track elements are set for clear at the controlling station at the end of such block 65 and at the entrance to the next block.

Danger conditions.

Under danger conditions, both magnets 18 are deenergized and the switches 17 open, whereby the coil 7 in passing the coils 14 will not receive the choking or detuning effect or impulse. Consequently, as usual whenever reaching a controlling station, the choke coils 7 and 8 passing over the non-magnetic rail section will result in a choking action in the circuit of the solenoid 19, whereby said solenoid is deenergized sufficiently to release the core 20, and the moment the core is released, the switch 30 leaves the contact 29 to keep the circuit of the solenoid open. The finger 57 drops on the worm 58 whereby the core 20 and switches 30 and 55 move downwardly in proportion to the movement of the vehicle, requiring a predetermined distance to be travelled by the vehicle before the switch 55 is removed from the contact 54. At the same time, the switch 30 being removed from the contact 29 immediately engages the contact 40 and connects the coil 7 in circuit with the solenoid 33 and magnet 39, as usual whenever passing a controlling station, such circuit including the generator 21, conductor 22, coil 7, conductors 24 and 44, solenoid 33, conductor 43, magnet 39, conductor 41, contact 40, switch 30 and conductor 32. The closing of such circuit will energize the solenoid 33 and magnet 39 to raise the pawl 37 and move said pawl for advancing the wheel 35 one step, the pawl engaging the first tooth 36 of said wheel. This action always occurs in passing a controlling station to provide a preliminary step of the wheel 35 that is required, thus conditioning the vehicle equipment for receiving caution or clear conditions when the danger producing means has been set into motion. The switches 17 being closed will result in the coil 7 passing the coils 14 without disturbing the energization of the solenoid 33 and magnet 39, and the wheel 35 therefore remains in its first step position with the armature projection 68 adjacent to and held by the magnet 67. As hereinbefore described, when the wheel 35 moves one step, the magnet 67 will remain energized. Thus, when the core 20 is released the switch 55 immediately engages the contacts 75 and 81, and the circuit of the magnet 67 is closed at once, such circuit including the battery 47, conductor 69, magnet 67, conductor 70, contacts 71, segment 72, conductors 73 and 74, contact 75, switch 55 and conductor 56. The switch 76 is therefore closed by the magnet 67, and the wheel 35 moving one step removes the segment 72 from the contacts 71, but the switch 76 now makes the connection between the conductors 70 and 74, to keep the magnet 67 energized while

the switch 55 is in its downward movement. Such conditions continue until the required distance of travel of the vehicle has been made, the finger 57 reaching the lower end 5 of the worm 58 and the switch 55 leaving the contact 54, which will open the circuit of the magnet 46 and release the switch 46'. Said switch 46' opens and thus establishes a danger or vehicle stopping condition, requiring the vehicle to be brought to a stop. Just after the switch 55 leaves the contact 54, the switch 30 engages the contact 61, and the coils 7 and 8 having moved beyond the non-magnetic rail section 10 are again connected in circuit with the solenoid 19 for energizing said solenoid. When the switch 30 engages the contact 61, the circuit of the solenoid 19 includes the generator 21, conductor 22, coil 7, conductors 24 and 25, coil 8, conductor 26, solenoid 19, conductor 28, contact 61, switch 30 and conductor 32. The coils 7 and 8 being over a magnetic portion of the rail will result in the solenoid 19 being energized, and during the upward movement of the core 20, the solenoid 33 and magnet 39 will remain energized because no choking effect in the coil 7 is obtained. The moment the solenoid 19 is reenergized, the switch 62 is attracted by the solenoid and brought against the contact 65, the pin 66 being in lowered position, and the switch 62 will therefore shunt the switch 30 between the conductors 28 and 32, to keep the circuit of the solenoid 19 closed during the upward movement of the core 20 and switch 30. However, as soon as the switch 30 engages the contact 29 to close the normal circuit of the solenoid 19, the pin 66 strikes the switch 62 and swings said switch 62 open and, thereafter the switch 62 will remain until the core 20 is lowered and the solenoid 19 reenergized subsequently. Thus, even though the switch 30 leaves the contact 61, the circuit of the solenoid 19 is kept closed by the switch 62 sufficiently long to enable the core 20 and switch 30 to be restored, the finger 57 swinging downwardly and dragging across the threads of the worm. The vehicle is thus brought to a stop and the core 20 and slide switches 30 and 35 restored to normal raised position. Furthermore, the switch 30 being removed from the contact 40 will open the circuit of the solenoid 33 and magnet 39 whereby the pawl 37 is restored to normal position. The switch 55 having been raised away from the contact 75 will also open the circuit of the magnet 67, thereby releasing the wheel 35 which will return to initial position. The switch 46', however, will remain down to require the stopping of the vehicle, although the other devices have all been returned to normal position.

65 The vehicle may be started under caution control after having reached a complete stop, with the switch 84 on the contacts 101, by closing the permissive starting switch 104. This will close the circuit of the solenoid 107, as hereinbefore described, and the core 109 will pull the flexible element 110 and turn the wheel 35 to its second step or caution position. In this position of the wheel 35 the armature projection 68 is adjacent to the magnet 67, the segment 52 75 is removed from the contacts 51 and now bridges the contacts 78, and the wheel 35 bridges the contacts 91. No matter how long the switch 104 is closed or how many times it is closed, the solenoid 107 is only 80 operable to turn the wheel 35 to its second or caution position and the vehicle equipment cannot be placed in clear condition by operating the switch 104. The control of the magnet 46 is now placed on the restrictive speed switch 84 to compel the slow movement of the vehicle through the remainder of the block. The circuit of the magnet 46 includes a conductor 79, contacts 78, segment 52 bridging said contacts 90 in the second position of the wheel 35, conductor 80, contact strip 82, switch 84, contact strip 83, conductor 86 and conductor 56. Therefore, the circuit of the magnet 46 through the switch 84 is closed as long 95 as the vehicle observes the speed limit, and the switch 46' is raised to permit the vehicle to proceed, but when the speed limit is exceeded, the switch 84 being removed from the contact strips 82 and 83 will open the circuit of the magnet 46 and apply the brakes. The circuit of the magnet 67 includes the battery 47, conductor 69, magnet 67, switch 76 (which has been closed by hand when the switch 104 is closed), contact 77, conductor 74, conductor 87, contacts 88, switch 89, conductor 90, contacts 91, wheel 35 in its second position, conductor 92, switch 93, contact 94, and conductor 95. This completes the caution maintaining circuit of the magnet 67, and the circuit of the solenoid 107 is broken immediately 100 when the vehicle is started by the removal of the switch 84 from the contacts 101, releasing the core 109 and flexible element 110 so as not to interfere with the return movement of the wheel 35 should the magnet 67 become deenergized. This caution condition will continue for the remainder 105 of the block, and when the vehicle reaches the next controlling station, the deenergization of the solenoid 107 will not only release the core 109, but will also release the caution holding or maintaining switch 93, and said switch 93 in dropping open will 110 open the circuit of the magnet 67, thereby 115 permitting the wheel 35 to return to initial position. This restores the normal circuit 120 of the magnet 46 including the contact 49, switch 46', conductor 50, contacts 51, switch 125 130

segment 52 in normal position, conductor 53, contact 54, switch 55 and conductor 56. The magnet 67 in being deenergized will release the switch 76, and the circuit of the magnet 67 between the conductors 70 and 74 is therefore not closed until the segment 72 returns into engagement with the contacts 71 in the initial position of the wheel 35. The core 20 may carry a spring-pressed dog 111 to positively open the switch 93 when the core 20 drops, so as to terminate caution control, but said dog 111 can be omitted. If such dog is used, it must be such that the core 20 can complete its downward movement without interference, when the switch 93 strikes its stop.

The arrangement of the contacts 51 and 78 and the segment 52 is preferably such that when the wheel 35 is turned forward to the second step position, the segment 52 opens the circuit between the contacts 51 slightly before said segment closes the circuit between the contacts 78 in changing to caution or restrictive speed control. Thus, although in making the change, the switch 46' may be released for an instant, said switch will be picked up at once again by the closing of the circuit of the magnet 46 through the contacts 78, whereas should the magnet 67 be deenergized by the breaking, shorting or grounding of the circuit of the magnet, under caution control, the segment 52 moving back away from the contacts 78 will break the circuit of the magnet 46 and release the switch 46' so that when the segment 52 bridges the contacts 51 the switch 46' will remain open, requiring the stopping of the vehicle. Therefore, should the caution maintaining circuit of the magnet 67 fail, the return of the wheel 35 under such condition would result in a danger or vehicle stopping condition because the switch 46' being released by the movement of the segment 52 away from the contacts 78 would not permit said switch 46' to be picked up even though the switch segment 52 returns to the contacts 51.

Caution conditions.

When the track devices or wayside signals are set for caution, one of the magnets 18 is energized and the other deenergized, so that one switch 17 is open and the other closed. When the vehicle reaches the non-magnetic rail section, the choking effect in the coils 7 and 8 is established as hereinbefore described, resulting in the solenoid 19 being deenergized and the core 20 moving downwardly, thereby connecting the solenoid 33 and magnet 39 with the coil 7 and moving the wheel 35 one step as usual under all conditions. When the coil 7 passes the coil 14 whose switch 17 is open, the magnetic flux from the core 9 passes through

the corresponding core 15, but the flow of the magnetic flux in opposite directions alternately is impeded or resisted by the action of the corresponding coils 14 and 16, thereby creating a choking effect in the coil 7 and detuning the circuit of the solenoid 33 and magnet 39 sufficiently to release the pawl 37 whereby it drops away from the wheel 35 and moves away from the solenoid 33 under the influence of the spring 38'. As soon as the coil 7 has passed the coil 14 with the switch 17 open, the choking effect is removed, whereby the solenoid 33 and magnet 39 are again energized, the pawl 37 taking hold of the second tooth 36 and moving the wheel 35 to its second or caution position. Although the armature projection 68 is attracted by the magnet 67, the torque due to the pawl 37, in rotating the wheel 35, is greater than the attractive force of said magnet 67. The armature projection 68' is brought adjacent to the magnet 67 to hold the wheel 35, and the segment 52 is removed from the contacts 51 and brought against the contacts 78, while the wheel 35 now bridges the contacts 91, the same as when the wheel 35 was set to caution position by the solenoid 107 as hereinbefore described. The magnet 46 is now controlled by the restrictive speed switch 84, requiring the vehicle to travel at a reduced speed through the block, as understood from the foregoing. The caution control is terminated at the end of the block by the opening of the switch 93 when the solenoid 19 is deenergized. During the time that the vehicle is passing the controlling station and moving in the predetermined distance of travel determined by the worm 58, the switch 55 being lowered engages the contact 81, whereby the switch 55 shunts the restrictive speed switch 84, delaying the reduction in speed until such distance has been travelled by the vehicle, after which, the solenoid 19 being energized to raise the core 20 will remove the switch 55 from the contact 81 and thus bring the switch 84 into control. When the switch 93 is opened at the end of the block, the magnet 67 is deenergized and the wheel 35 turned back to initial position. Under caution control, with the wheel 35 in its second step position, the vehicle must travel below the permitted speed or the switch 84 will open the circuit of the magnet 46, thus retarding the vehicle until it is slowed down to the required restricted speed.

Clear conditions.

In clear conditions, both magnets 18 are deenergized and both switches 17 open, so that when the coil 7 passes the coils 14, two impulses are transmitted to the vehicle equipment. The solenoid 19 is deenergized by the choking effect in the coils 7 and 8

when the non-magnetic rail section is reached, thereby starting the solenoid 20 on its downward journey, and the solenoid 33 and magnet 39 are simultaneously connected with the coil 7, and the wheel 35 moved the initial or preparatory step. In passing the first coil 14, a choking effect is obtained in the coil 7, to release the pawl 37, and when the coil 7 has moved past the first coil 14, the choking effect is terminated and the solenoid 33 and magnet 39 are reenergized, to actuate the pawl 37 and move the wheel 35 a second step, to obtain caution conditions, but the switch 55 engaging the contact 81 bridges the switch 84 to prevent the magnet 46 being deenergized even when travelling at a high speed in passing the controlling station during the required distance of travel of the vehicle. When the coil 7 passes the second coil 14 the solenoid 33 and magnet 39 are again deenergized and then reenergized, whereby the pawl 37 in being actuated moves the wheel 35 a third step. This action occurs before the switch 55 is removed from the contact 54, and the pin 98 striking the arm 96 will swing the switch 89 open, thereby opening the circuit of the magnet 67 as hereinbefore described, it being noted that in the second step position of the wheel 35, the circuit of the magnet 67 includes the switch 89, contacts 91 and wheel 35 and switch 93. This opening of the switch 89 will deenergize the magnet 67 and permit the wheel 35 to return to initial position. The magnet 67 being deenergized releases the switch 76 so that said switch opens, and the circuit of the magnet 67 is then broken at the switch 76 and also at the contacts 71 until the wheel 35 is restored to initial position when the segment 72 again engages the contacts 71. This will assure of the magnet 67 remaining deenergized when the armature projections 68 and 68' move past said magnet in the return movement of the wheel 35. When the wheel 35 returns to initial position, the pin 97 striking the arm 96 will again close the switch 89.

When the vehicle has moved the required distance in passing the controlling station, so that the core 20 and switches 30 and 55 are restored by the engagement of the switch 30 with the contact 61, as hereinbefore explained, normal clear conditions are restored, the wheel 35 having been released and returned to initial position and the magnet 46 having been kept energized by the failure of any of its circuits being broken as established by the movement of the wheel 35 and switch 55. Thus, when passing the controlling station, the switch 55 engaging the contact 81 keeps the circuit of the magnet 46 closed under caution conditions with the wheel 35 moved two steps, thereby pre-

venting the switch 84 from controlling the magnet 46 until the required distance has been travelled. If, during the meantime, a second impulse is transmitted to the vehicle equipment, the wheel 35 is restored to initial position. To explain the successive circuits of the magnet 46 in their order of occurrence, it will be noted that in the initial position of the wheel 35, the circuit of the magnet 46 includes the contact 49, switch 46', conductor 50, contacts 51, segment 52, conductor 53, contact 54, switch 55, conductor 56, battery 47 and conductor 48, so that if the wheel 35 is not advanced to its second step or caution position, the switch 55 in moving downwardly away from the contact 54 will deenergize the magnet 46 and require the stopping of the vehicle. The wheel 35 always makes one step in passing a controlling station, but the circuit of the magnet 46 in the first step position of the wheel 35 is the same, the segment 52 remaining in engagement with the contacts 51, and although the magnet 67 is energized by the engagement of the switch 55 with the contact 75, the control of the magnet 46 is the same. In the second step position of the wheel 35, the segment 52 is removed from the contacts 51 and contacts with the contacts 78, and during the movement of the vehicle in the required distance of travel when passing a controlling station, the circuit of the magnet 46 includes the conductor 79, contacts 78, segment 52, conductor 80, contact 81, switch 55, conductor 56, battery 47 and conductor 48. The switch 55 thus, in the second position of the wheel 35, keeps the circuit of the magnet 46 closed. However, when the required distance of travel has been made by the vehicle and the core 20 is restored to remove the switch 55 from the contact 81, with the wheel 35 in its caution position, the circuit of the magnet 46 now includes the conductor 79, contacts 78, segment 52, conductor 80, contact strip 82, restrictive speed switch 84, contact strip 83, conductors 86 and 56, battery 47, and conductor 48. This brings the control of the magnet 46 under the restrictive speed switch 84 requiring speed control to be observed.

In order to prevent the magnet 46 being deenergized while the wheel 35 is returning to initial position and the switch 55 is being raised, under clear conditions, the arm 96 of the switch 89, when said switch is moved by the pin 98, bridges a pair of contacts 112, one contact being connected by a conductor 113 with the conductor 79 and the other contact 112 being connected by a conductor 114 with the conductor 95. Consequently, when the wheel 35 is moved the third step to remove the switch 89 from the contacts 88, the arm 96 bridges the contacts 112 until the wheel 35 is returned to initial position, and

the circuit of the magnet 46 is held closed by way of the conductor 79, conductor 113, contacts 112, switch arm 96, conductor 114, conductor 95, battery 47 and conductor 48. This avoids the magnet 46 being deenergized during the restoration of the ratchet device 34 and core 20, but as soon as the wheel 35 is returned to initial position, the pin 97 removes the switch arm 96 from the contacts 112 and brings the switch 89 against the contacts 88. This opens the circuit of the magnet 46 by way of the contacts 112, although the circuit of the magnet 46 is now closed by way of the switch segment 52 and switch 55. It will be noted that when the solenoid 33 and magnet 39 are re-energized after passing the second coil 14 with the corresponding switch 17 open, the pawl 37 being held to the wheel 35 by the magnet 39 and being attracted toward the solenoid 33, will hold the wheel 35 against return movement, until the required distance has been travelled, so that the core 20 and switches 80 and 55 are restored, in which event the solenoid 33 and magnet 39 being deenergized by the removal of the switch 30 from the contact 40 will release the wheel 35. Therefore, before the wheel 35 is returned to initial position, the switch 55 is restored to the contact 54, and the switch arm 96 keeping the magnet 46 energized will thus result in the completion of the original circuit of the magnet 46 before the switch arm 96 is removed from the contacts 112 when the wheel 35 is restored to initial position.

Having thus described the invention, what is claimed as new is:—

1. Vehicle controlling apparatus including a translating device having a run-down member for obtaining a predetermined condition of vehicle control, a second translating device operable for averting such condition and obtaining other conditions during the run-down movement of said member, a responsive device controlling the first-named translating device to start the run-down movement of said member, and means for changing the control by said responsive device from the first-named to the second-named translating device.

2. Vehicle controlling apparatus including a translating device having a run-down member for obtaining a predetermined condition of vehicle control, a second translating device for averting such condition and obtaining other conditions during the run-down movement of said member, a responsive device, and means for normally establishing circuit connections between the responsive device and first-named translating device and for changing the circuit connections, when the first-named translating device has been brought into operation, to start the run-down movement of said member and to

connect the responsive device with the second-named translating device.

3. Vehicle controlling apparatus including a primary translating device having a run-down member for obtaining a predetermined vehicle controlling condition, a secondary translating device for averting such condition and obtaining other conditions during the run-down movement of said member, a responsive device normally controlling the primary translating device, means at the controlling station for affecting said responsive device to start the run-down movement of said member, means for changing the control of the responsive device, when said member has started its run-down movement, to control the secondary translating device by said responsive device, and other means at the controlling station for affecting the responsive device to control the secondary translating device.

4. Vehicle controlling apparatus including a primary translating device having a run-down member, a secondary translating device, a responsive device, means for normally connecting the responsive device with the primary translating device and operable, when said member starts its run-down movement, for connecting the responsive device with the secondary translating device, and means at the controlling station for affecting the responsive device to start said member in its run-down movement and to control the responsive device when connected to the secondary translating device.

5. Vehicle controlling apparatus including a primary translating device having a run-down member, a secondary translating device, a responsive device, means whereby the responsive device normally controls the primary translating device and, when the run-down member is started in its movement, the responsive device then controls the secondary translating device, means at the controlling station for affecting said responsive device each time it passes such station for bringing the run-down member into action, and controlled means at the station for selectively affecting the responsive device after it obtains control of the secondary translating device.

6. Vehicle controlling apparatus including a primary translating device, a secondary translating device, a non-magnetic section in a rail of the track at the controlling station, a responsive device inductively responsive to said rail and normally controlling the primary translating device to start said device into operation when the responsive device reaches the non-magnetic rail section, means for changing the control of the responsive device from the primary to the secondary translating device when the primary translating device is started into operation, and means associated with said non-

magnetic rail section for affecting said responsive device to control the secondary translating device.

7. Vehicle controlling apparatus including a primary translating device, a secondary translating device, a non-magnetic section in a rail of the track at the controlling station, a responsive device inductively responsive to the rail and controlling the primary translating device for starting said device into operation when the responsive device reaches the non-magnetic rail section, means for changing the control of the responsive device from the primary to the secondary translating device when the primary translating device has started into operation, and controlled means associated with said non-magnetic rail section with which the responsive device is magnetically cooperable for the control of the secondary translating device.

8. Vehicle controlling apparatus including a movable member, responsively controlled means for advancing said member step by step, means for establishing restrictive-speed conditions in one advanced position of said member, means for holding said member in such position, means controlling said holding means for releasing said mem-

ber for return movement, and means operable in order that the advance movement of said member beyond such position will control the holding means to release said member for return to initial position.

9. Vehicle controlling apparatus including a primary responsively-controlled translating device for obtaining a predetermined condition of vehicle control, a secondary translating device including a movable member and intermittently operated means for moving said member step by step, means operable when said member is advanced to one position for averting the aforesaid controlling condition and obtaining a restrictive speed condition, means for holding said member in such position, means controlling said holding means for releasing said member for return movement when the vehicle reaches a predetermined position of the track, and means operable in order that the advance movement of said member beyond said position will control the holding means to release said member for return to initial position and to avert both of said conditions.

In testimony whereof I hereunto affix my signature.

ALFRED L. RUTHVEN.
